UNITED STATES PATENT OFFICE.

ALBERT B. HERRICK, OF CLEVELAND, OHIO, ASSIGNOR TO MATIE C. MESSLER, OF PAWTUCKET, RHODE ISLAND.

INDUCTOR.

1,177,701.

Specification of Letters Patent.

Patented Apr. 4, 1916.

Application filed May 31, 1912. Serial No. 700,594.

To all whom it may concern:

Be it known that I, ALBERT B. HERRICK, a citizen of the United States, and a resident of Cleveland, county of Cuyahoga, and 5 State of Ohio, have invented a new and useful Improvement in Inductors, of which the following is a specification, the principle of the invention being herein explained and the best mode in which I have contemplated 10 applying that principle, so as to distinguish it from other inventions.

The present invention relates to a new and improved method for inducing a current in a coil. The current is induced in an induction coil which, while in construction similar 15 to that now used for the same purpose, is totally different in operation. The present induction coil comprises an iron core surrounded by primary and secondary windings. It differs from the usual armature by 20 being fixed and immovable. A magnet is disposed adjacent to the coil and the current is induced by varying the disposition of the magnetic circuit both in direction and 25 intensity. Mechanical means are provided for thus shifting the magnetic circuit, and such action may be produced by either rotary or reciprocating motion of a single member.

30 In order to more clearly bring out the operation of apparatus for inducing a current by my new method, I show the same in connection with a spark plug adapted to be inserted in the compression chamber of 35 an internal combustion or explosive engine. In such a device the operating member, or means for shifting the magnetic circuit, will preferably be operated by the compression in the chamber, both for simplicity of construction and for the purpose of having the 40 movement of such member (and the increase in the intensity of the current) responsive to and following the movement of the piston in the compression chamber.

45 The induction coil may be designed for either high or low tension current, and the system will be provided with means for handling either type. That is, if high tension is used, then means must be provided to break 50 the circuit externally of the cylinder, assuming the invention applied to ignition mechanism, while with a low tension the current

will be broken in the cylinder. High tension is at present so universally used on small engines that I have here shown only mechanism adapted to such a system, as that will be my preferred type of ignition. It will be obvious, however, that only slight mechanical changes will be necessary to adapt the mechanism to a low tension system. 55 60

The annexed drawings and the following description set forth in detail certain mechanism embodying the invention, such disclosed means constituting, however, but one of the various mechanical forms in which 65 the principle of the invention may be used.

In said annexed drawings:—Figure 1 is a view in perspective of a coil and magnet illustrating the construction of my device in its general form; Fig. 2 is an end elevation 70 of my device applied to an igniter; Fig. 3 is a view similar to Fig. 2, but showing the movable member of the igniter in its raised position; Figs. 4 and 5 are views in perspective of the movable member and the induction coil to be used in the igniter; Fig. 6 is a diagrammatic view showing the connections in my device; Fig. 7 is a sectional view 75 on the line 7—7 in Fig. 2; Fig. 8 is a section on the line 8—8 showing the construction of 80 the springs and the contact points on top of the movable member of my igniter, and Fig. 9 is a central vertical section of a modification of my device.

In Fig. 1 I show a soft core 1, about 85 which there is wound a primary coil 2 and a secondary coil 3. On either side of this core are disposed permanent magnets 4 and 5, and on either end of the core 1 there are mounted arms 6 which are adapted, upon 90 partial rotation, to connect up the core with either one of these magnets. In this way the direction of the magnetic current may be reversed by changing these arms from their connection from one of the magnets to 95 the other. There is no necessity for rotating the coil and core to change the direction of the magnetic flux as this may be done by merely rotating these arms, or by moving a suitable connecting member, such as a 100 keeper, which is shown in the application of my device to ignition mechanism. The magnetic circuit through the core induces a current in the primary and secondary coils,

which will vary in direction and intensity according to the disposition of the magnetic circuit.

In Fig. 2 there is shown a laminated permanent magnet 9 which is formed of six separate iron strips 10 having a brass strip 11 between each set of three iron strips. The magnet is of horse-shoe form, as shown, and at the two ends the brass strip is cut away or slotted, adapting it to receive the brass strips 12 to which are attached a keeper 13. The latter is formed of two spaced horizontal brass strips 14 and two side iron strips 15 attached to the brass strips, these last-named strips sliding in the slots in the magnet. This keeper forms the connecting or movable member, referred to in the preceding paragraphs, for the purpose of shifting the magnetic circuit through the induction coil. Around the magnet there is placed an aluminum casing 16, and in this casing there is mounted a horizontal shaft 17 bearing fixedly thereon an arm 18 which carries a stop 19. Loosely mounted on this shaft is a lever 20 which is attached by means of a link 21 to the keeper. At one end of the lever 20 is mounted a stub shaft 71 and rotatably carried on such shaft is a second lever 22 having one end 23 adapted to engage the stop 19 upon being rotated about the shaft 21. The other end of such lever is formed into a latch 24 and is engaged by the spring 25 which is mounted on the block 26 and bears a platinum contact point 27 adapted to normally engage a similar contact point 28 on the member 29, also mounted on said block 26. The engagement of these two points closes the primary circuit, as will be seen in Fig. 6.

The induction coil comprises a core 30 (see Figs. 5 and 7), a primary coil 31 and a high tension secondary coil 32. At either end of the core is mounted a contact plate 33 having stepped edges as shown. The induction coil is placed within the keeper 13 and is fixed by attaching it to the back of the outer aluminum casing. The keeper 13 is hollow, as shown, and on its inside has steps 34 adapted to engage the steps on the core. It will be noticed that the steps on the keeper are disposed so that in either upper or lower position of the latter there will be a contact between the same and the core although the circuit will be different in such two positions. In the upper position of the keeper the disposition of the magnetic circuit is indicated by the arrows 40, in the lower position of the keeper the magnetic circuit is indicated by the arrows 41.

The casing 16 terminates in a collar 42 engaging the casing 43 of a spark plug which is adapted to engage an engine cylinder 44 (see Figs. 2 and 3). The spark plug casing is apertured at its lower end and contains a piston member 45 slidable in such

aperture. Such piston is extended to permit of attachment to the keeper and will be operated by the compression in the engine cylinder, as will be readily understood. In this way the action of the keeper can be made to follow the movement of the engine piston.

Attached to the coil is a tube 46 which passes through the piston and forms a guide for the same. This tube incloses the lead wire 47 from the secondary coil to the spark plug terminal 48. The other wire 49 from the secondary coil is grounded on the engine cylinder and the connection to the other terminal 50 is through this ground. The piston and tube are insulated from the plug casing by suitable packing in the usual manner.

In order to return the keeper to its lower position I employ an elliptic spring 51 which rests on the top of the keeper. In the top of the brass strip in the magnet is a threaded aperture engaged by a brass tube 52 which bears on the top of the elliptic spring. The tube 52 has a square aperture 90 therein engaged by a rod 53 extending through an aperture in the top of the keeper and having a stop 54 on its lower end adapted to engage the keeper when such rod is lifted, thereby raising the keeper. On the top of the rod is a handle 56. By rotating this handle the tube is rotated thus moving it vertically and increasing or decreasing the tension on the spring 51, as desired. In this way the movement of the keeper may be to some extent controlled and the device adapted to compression of the engine to which it is attached.

In operation the igniter may be set to give a spark at any desired point in the cycle by controlling the movement of the keeper through the spring 51 and by setting the stop 19, by rotating the arm 18 by means of the crank 57 which projects beyond the casing. As the engine piston compresses the gas the piston in the spark plug is forced upward, such movement beginning only when the pressure in the cylinder is greater than the pressure of the spring 51, and the pull of the magnets. The keeper is thus raised to its upper position, thus raising lever 20 which rotates about the shaft 17. Such movement causes upward movement of the lever 22, the end 24 being held fixed by the spring 25. When the end 23 strikes the stop 19, the lever 22 will pivot about this point, thus raising the spring 25 and separating the contact points 27 and 28. This breaks the circuit and permits the current which has been induced to flow to the terminals of the spark plug and fire the compressed gas. This is the mechanical operation of the device. The electrical operation is more clearly shown by starting with the action when the keeper is beginning its

downward movement. As the keeper moves downward a current is induced in the coils. The circuit is closed at this time, however, as shown in Fig. 6. As the keeper reaches 5 the lower position and is moved upward the magnetic circuit is shifted and the direction of the lines of force in the coil is changed. The current is built up by what was induced during the downward movement and while slow to reach its maximum 10 strength, were the movement of the keeper continued, this is effected by opening the circuit by breaking the contact points 27 and 28 and a strong spark is obtained 15 across the spark plug terminals. The wiring connections are readily seen from Fig. 6 and need no further explanation. A condenser 70 of the usual type is shown connected across the primary coil.

20 In Fig. 9 there is shown a modified form of spark plug which may be used if desired. In such form the piston 60 is disposed in an offset chamber 61 connected by a passage 62 with the aperture 63 in the 25 plug proper. The tube 64 containing the wire from the coil passes through the keeper as in my preferred form. In other respects the modified form is substantially like the preferred construction. It is possible in either form to form a chamber 65 30 as in Fig. 9, between the piston and the rear of the chamber, in order to utilize the compression of the air therein to assist in forcing the piston and keeper to the lower 35 position.

The advantages of my apparatus are its 40 extreme simplicity, few moving parts and efficient action. The spark obtained is strong and the operation is automatic and not liable to get out of order. When applied to ignition mechanism, a separate 45 device will be attached to each cylinder, but the shaft 17 may be continued through the aligned devices in order to permit of simultaneous and equal spark advance on all cylinders by movement of a single lever. A 50 spark may be secured in the cylinder by simply pulling up the handle 56, and the device may be adjusted to any engine by 55 changing the pressure on the spring 51 in the manner indicated, or by shifting the advance lever.

The features of my invention to which I 60 desire to call particular attention, are my improved method of inducing a current in a coil, the simple and efficient apparatus for producing a high tension current for an engine operated by the compression of the engine or in some other manner, and the general construction of the specific igniter here shown.

Other modes of applying the principle of my invention may be employed instead of the one explained, change being made as regards the mechanism herein disclosed, pro-

vided the means stated by any of the following claims or the equivalent of such stated means be employed.

I therefore particularly point out and distinctly claim as my invention:—

1. The combination of a spark plug; an induction coil connected to said plug; the circuit through the coil being normally closed; mechanical means operable by the compression in the engine cylinder for shifting the lines of force and thereby inducing a current in said coil and simultaneously breaking said circuit; and other means adapted to vary the pressure required to operate said first-named means.

2. The combination of a spark plug; an induction coil connected to said plug; the circuit through the coil being normally closed; a movable keeper operable by the compression in the engine cylinder for shifting the lines of force and thereby inducing a current in said coil and simultaneously breaking said circuit; and means adapted to vary the pressure required to operate said keeper.

3. The combination of a spark plug having an aperture therein; a movable member mounted in such aperture and operable by the compression in the engine cylinder; an induction coil connected to said plug, the circuit through the coil being normally closed; a movable keeper attached to and operable by said member for shifting the lines of force and thereby inducing a current in said coil, and simultaneously breaking said circuit; and means adapted to vary the pressure required to operate said keeper.

4. The combination of a spark plug having an aperture therein; a movable member mounted in such aperture and operable by the compression in the engine cylinder; an induction coil connected to said plug; a movable contact member in said circuit and normally closing the same; a magnetic circuit through said induction coil; and a movable keeper operable by said movable member for shifting said magnetic circuit through said coil, thereby inducing a current and simultaneously moving said contact member thereby breaking the electrical circuit.

5. The combination of a spark plug having an aperture therein; a piston mounted in such aperture and operable by the compression in the engine cylinder; an induction coil connected to said plug; a movable resilient contact member in such circuit and normally closing the same through said coil; a magnetic circuit through said induction coil; a movable keeper operable by said piston for shifting the magnetic circuit through said coil; a pivotally mounted member having one end connected at its axis to said keeper and operable thereby; one end of

said member engaging said resilient contact member; and a stop adapted to engage the other end of said pivotally mounted member, upon the raising of the same by said keeper, whereby said contact member is actuated to break said circuit.

6. The combination of a spark plug having an aperture therein; a piston mounted in such aperture and operable by the compression in the engine cylinder; an induction coil connected to said plug; a movable resilient contact member in such circuit and normally closing the same through said coil; a magnetic circuit through said induction coil; a movable keeper operable by said piston for shifting the magnetic circuit through said coil; a pivotally mounted member having one end connected at its axis to said keeper and operable thereby; one end of said member engaging said resilient contact member; a stop adapted to engage the other end of said pivotally mounted member, upon the raising of the same by said keeper, whereby said contact member is actuated to break said circuit; and means for adjusting the position of said stop.

7. The combination of a spark plug having an aperture therein; a piston mounted in such aperture and operable by the compression in the engine cylinder; an induction coil connected to said plug; a movable resilient contact member in such circuit and normally closing the same through said coil; a magnetic circuit through said induction coil; a movable keeper operable by said piston for shifting the magnetic circuit through said coil; a pivotally mounted member having one end connected at its axis to said keeper and operable thereby; one end of said member engaging said resilient contact member; a stop adapted to engage the other end of said pivotally mounted member, upon the raising of the same by said keeper, whereby said contact member is actuated to break said circuit; means for adjusting the position of said stop; and means adapted to retain said keeper in its normal position.

8. The combination of a spark plug having an aperture therein; a piston mounted in such aperture and operable by the compression in the engine cylinder; an induction coil connected to said plug; a movable resilient contact member in such circuit and normally closing the same through said coil; a magnetic circuit through said induction coil; a movable keeper operable by said piston for shifting the magnetic circuit through said coil; a pivotally mounted member hav-

ing one end connected at its axis to said keeper and operable thereby; one end of said member engaging said resilient contact member; a stop adapted to engage the other end of said pivotally mounted member, upon the raising of the same by said keeper, whereby said contact member is actuated to break said circuit; means for adjusting the position of said stop; resilient means adapted to retain said keeper in its normal position; and means for adjusting the force of said resilient means.

9. The combination of a spark plug having an aperture therein; a piston mounted in such aperture and operable by the compression in the engine cylinder; an induction coil connected to said plug; a movable resilient contact member in such circuit and normally closing the same through said coil; a magnetic circuit through said induction coil; a movable keeper operable by said piston for shifting the magnetic circuit through said coil; a pivotally mounted member having one end connected at its axis to said keeper and operable thereby; one end of said member engaging said resilient contact member; a stop adapted to engage the other end of said pivotally mounted member, upon the raising of the same by said keeper, whereby said contact member is actuated to break said circuit; and means for manually breaking said electrical circuit when desired.

10. The combination of a spark plug having an aperture therein; a piston mounted in such aperture and operable by the compression in the engine cylinder; an induction coil connected to said plug; a movable resilient contact member in such circuit and normally closing the same through said coil; a magnetic circuit through said induction coil; a movable keeper operable by said piston for shifting the magnetic circuit through said coil; a pivotally mounted member having one end connected at its axis to said keeper and operable thereby; one end of said member engaging said resilient contact member; a stop adapted to engage the other end of said pivotally mounted member, upon the raising of the same by said keeper, whereby said contact member is actuated to break said circuit; and means for manually operating said keeper when desired.

Signed by me this 28th day of May, 1912.
ALBERT B. HERRICK.
